(57) **CLAIM**

The ornamental design for a hair forming device, as shown and described.

DESCRIPTION

FIG. 1 is a front perspective view of my new design for a hair forming device in the open position.

FIG. 2 is a front side elevation view of the hair forming device in the closed position.

FIG. 3 is a back side elevation view of FIG. 2, the power cord attachment location shown in dotted lines is for illustrative purposes only and is not part of the claimed design.

FIG. 4 is a left side elevation view of FIG. 2, the right side elevation view is a mirror image.

FIG. 5 is a top plan view of FIG. 2; and,

FIG. 6 is a bottom plan view of FIG. 2.
